UNITED STATES PATENT OFFICE.

CHARLES D. ORCUTT, OF DAYTON, OHIO.

DESIGN FOR A STOOL.

SPECIFICATION forming part of Design No. 36,266, dated March 31, 1903.

Application filed March 2, 1903. Serial No. 145,845. Term of patent 7 years.

To all whom it may concern:

Be it known that I, CHARLES D. ORCUTT, a citizen of the United States, residing at Dayton, in the county of Montgomery and State of Ohio, have invented a certain new, original, and ornamental Design for a Stool; and I do declare the following to be a full, clear, and exact description of the invention, such as will enable others skilled in the art to which it appertains to make and use the same, reference being had to the accompanying drawing, and to the letters of reference marked thereon, which form a part of this specification.

15 The drawing is an elevation of a stool made in accordance with my new and ornamental design.

The leading or characteristic features of the design consist in the leg A, which terminates at its lower end in claws B and at its upper end in ornamentations C, said ornamentations consisting of scrollwork D, which is inclosed by two upright bars E. The leg immediately below the ornamentations C ter-

minates in a series of ornamentations F, which consist of relief-work in the nature of a representation of hair. This surface ornamentation F is inclosed by marginal bars G, which extend throughout the length of the leg on each side thereof. Between each two of such legs there is ornamental skirting H, having the characteristic features appearing in the drawing.

I designates a surface above the skirting which is devoid of any ornamentations. Above this surface I there is an ornamental beading J.

Having described my invention, what I claim as new, and desire to secure by Letters Patent, is—

20 The ornamental design for a stool as herein shown and described.

In testimony whereof I affix my signature in presence of two witnesses.

CHARLES D. ORCUTT.
